UNITED STATES PATENT OFFICE.

GUSTAVE E. W. MILLER, OF BOSTON, MASSACHUSETTS.

FOLDING TOOTHBRUSH.

Application filed April 16, 1919. Serial No. 290,456.

To all whom it may concern:

Be it known that I, GUSTAVE E. W. MILLER, a citizen of the United States, residing at Boston, in the county of Suffolk 5 and State of Massachusetts, have invented a new and useful Folding Toothbrush, of which the following is a specification.

This invention relates to a tooth brush casing, adapted to hold a tooth brush in such a manner that it can be folded inside the casing, for permitting it to be carried in the pocket readily.

The principal objects of the invention are to provide a construction which will be 15 sanitary and will occupy very little space; to provide an improved clasp and hinge therefor, and more specifically to provide a convenient form of detachable connection by which the tooth brush may be supported 20 on the casing while in use and firmly held in the proper position when it is folded inside the casing. This is so arranged that it is contacted by the engaging walls of the casing and cover to firmly hold the 25 brush in position, when in use.

The invention also involves improvements in other details of construction including the particular construction of the casing and cover itself, the means for hinging the 30 parts together and locking them together in closed position.

Reference is to be had to the accompanying drawings, in which—

Fig. 1 is a side view of a preferred embodiment of this invention, showing the brush in one position for use;

Fig. 2 is a back view of the same;

Fig. 3 is a view of the casing and cover opened with the brush shown in the casing 40 in full lines, and projecting therefrom in dotted lines in position for use, in the same location as that shown in Fig. 1;

Fig. 4 is a side view of the same with the parts shown in a different position;

Fig. 5 is an enlarged sectional view on the line 5—5 of Fig. 4, showing the means for connecting the casing with the cover;

Fig. 6 is a side view like part of Fig. 3, enlarged;

Fig. 7 is a view showing parts in section and illustrating in dotted lines how the brush can be detached from the pivoted link and casing, and

Figs. 8 and 9 are a plan and inside view 55 respectively of a modification.

The invention is shown in a form in

which it involves a casing 10 and a cover 11 pivoted thereto, these two parts are shown as formed of thin sheet material, as for example, celluloid or metal, with perforations to afford free circulation of air when it is closed. This cover is pivoted to the casing by means of integral cylindrical hubs 12 on the cover and casing alternating with each other, and a pin 13 extending through them. These are cylindrical in shape formed of the sheet material, and bored out to afford a passage for the pin. In this way the two parts are pivotally connected together along the whole of the short 60 side, and this ensures the closing of the parts together always in the same position, because the hinge is of such a nature that it is not likely to get out of place.

The casing and cover are of a general rectangular shape but with an extension 14 at one end. The extensions on the two parts register with each other and tend to contract at the end to form a passage 15 for the shank of the tooth brush as will appear. 75 It may be noticed at this point that both the casing and cover are provided with a pair of studs or projections 16 located in the contracted end portion in alignment with each other.

Preferably on the interior of the casing there is located a bracket 20 which supports a pivoted link 21 passing through it, and having two arms extending upwardly parallel with each other on opposite sides of 90 this bracket. These arms are provided with separated converging ends 22 in alignment with each other. This is for detachable connection with the tooth brush shank 23, which is provided at the end and on each 95 side with a pair of opposite shallow grooves 24 for receiving the ends 22. At the ends of these grooves are two opposite depressions 25 into which the ends 22 enter when the parts are pressed fully into position. 100 Thus the ends 22 constitute a pivot on which the shank 23 is mounted and by which it is connected with the casing. The shank is also provided with two depressions 26 on each side for receiving the studs 16. The 105 object of this connection is to cause the studs to enter the sockets and steady the tooth brush shank in the casing when the casing is closed and the tooth brush is extended as shown in Figs. 1 and 4.

The position of the brush when the casing is to be closed is indicated in Fig. 3 in full

lines. The brush is supported in the casing by its pivotal connection with the link 21 and if the brush is used in the position shown in Fig. 1 it need not be detached from 5 this connection when it is to be folded in the casing, but if it is to be used in the position shown in Fig. 4, which is most convenient for many people, the brush has to be removed from the pivoted link 21 and reversed 10 in order to enclose it in the casing. This can be done, in the manner indicated in dotted lines in Fig. 7 by simply pulling on the brush. This releases the ends 22 from the notches or depressions 25 and allows the 15 ends to slide along the grooves 24 as the shank is withdrawn. Then it is reversed and put back in position in a similar manner.

It is to be noticed that when the brush is 20 folded back in the position shown in full lines in Fig. 3, and the cover closed, the converging edge walls of the casing and cover come into contact with the link 21 and hold it in position, so that the brush 25 is held not only by the studs 16 but by these links. Therefore, it will not wobble in the casing or come into such position that its bristles will engage the walls of the casing.

It is to be noticed that I have provided 30 a fastening device in the form of a hinged clasp 27 having side flanges 28, that come down over the box and cover when it is folded down into closed position. This is 35 preferably inset into the box and cover by providing depressions 29 in the course of manufacture.

In Figs. 8 and 9 I have shown a modification 40 in which the pivotal link projects through notches 30 in the edges of the casing and cover, which clamp it solidly when closed.

It is to be observed therefore that this 45 device is firm and solid in construction, holding the brush securely in either folded or projected position, so as to prevent any movement of the brush relative to the casing. This forms a receptacle which is entirely closed at all points but properly ventilated and firmly held by the hinge and 50 clasp.

Although I have illustrated and described only one form of the invention, I am aware 55 of the fact that modifications can be made therein by any person skilled in the art without departing from the scope of the invention as expressed in the claims, therefore I do not wish to be limited to all the details of construction herein shown and described, but

60 What I do claim is:

1. In a folding tooth brush, the combination 65 with a casing, of a movable link connection pivoted therein, and a tooth brush pivotally connected with said link connection and readily detachable therefrom,

2. In a folding tooth brush, the combination with a casing, of a link pivoted therein, at a distance from the end of the casing, and a tooth brush shank pivotally mounted on 70 said link and readily detachable therefrom. 70

3. In a folding tooth brush, the combination with a casing, of a link pivoted therein at a distance from the end of the tooth brush, and a tooth brush shank detachably and pivotally mounted on said link, said 75 link having yielding projections in alignment extending toward each other and the tooth brush shank having opposite depressions for receiving said projections.

4. In a folding tooth brush, the combination with a casing, of a link pivoted therein having yielding projections in alignment 80 extending toward each other, and a tooth brush shank having opposite depressions for receiving said projections, said projections 85 and depressions being alike on both sides so that it is reversible.

5. In a folding tooth brush, the combination with a casing, of a link pivoted therein having yielding projections in alignment 90 extending toward each other, and a tooth brush having a shank provided with two opposite longitudinal grooves in its end for receiving the projections, said grooves terminating in two opposite depressions so that 95 the shank can be pivotally and detachably connected to the link.

6. In a folding tooth brush, the combination with a casing and a cover pivotally connected together, said casing and cover having 100 a reduced end, of a pivotal connection therein having separated ends in transverse alignment, and a tooth brush detachably connected with said separated ends, and having its end located in the reduced end, the 105 walls of which engage the separated ends of the pivotal connection to help hold them in position and prevent detachment of the brush.

7. In a folding tooth-brush, the combination with a casing, of a link pivoted thereto, and a tooth-brush shank pivotally mounted on 110 said link, said link having opposite yielding projections in alignment extending toward each other and the tooth brush shank 115 having opposite depressions for receiving said projections.

8. In a folding tooth-brush, the combination with a casing, of a link pivotally mounted therein, and a tooth-brush shank 120 pivotally connected with the link and detachable therefrom by pulling it in any direction directly away from the point of pivotal support of the link.

9. A folding tooth-brush casing comprising 125 two right and left parts pivotally connected along one straight side and having a reduced end affording a passage formed by the two parts for receiving a tooth-brush shank, said shank and reduced end 130

having opposite symmetrical inter-engaging projections and depressions for locating and steadyng the tooth-brush in said passage and means independent of said proje⁵ction and depressions for pivotally connecting the brush with the casing.

10. In a folding tooth brush, the combination with a two-part casing and brush, said two parts of the casing having means for holding the shank of the brush, of

swinging means permanently connected to one of said parts and extending within it from the end for positively holding the shank against longitudinal withdrawal when it is held between the two parts of ¹⁵the casing.

In testimony whereof I have hereunto affixed my signature.

GUSTAVE E. W. MILLER.
